UNITED STATES PATENT OFFICE.

THOMAS HEDDOCK, OF PLAINS, PENNSYLVANIA.

CAR DOOR.

Application filed May 14, 1921. Serial No. 468,552.

To all whom it may concern:

Be it known that I, FRANK HEDDOCK, a citizen of the United States, residing at Plains, in the county of Luzerne and State of Pennsylvania, have invented new and useful Improvements in Car Doors, of which the following is a specification.

This invention relates to improvements in car doors, the principal object of the invention being to provide a door made of sections so connected together that the door can be pulled up to occupy a position underneath the roof of the car.

Another object of the invention is to provide guiding means for the door and means for raising the door.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a front view of a portion of a car showing my improved door thereon.

Figure 2 is a sectional view on line 2—2 of Figure 1.

Figure 3 is a cross sectional view on line 3—3 of Figure 1.

Figures 4 and 5 are detail views.

In these views, 1 indicates the car and 2 the door openings therein. Guideways 3 are formed at the sides of each door opening, said guideways being extended underneath the roof of the car as shown at 4, the extended part of the guideways being of curved formation to conform to the shape of the roof.

Each door 5 is composed of a number of sections 6, each section being provided with the slotted flanges 7 at its ends, the flanges being of greater length than the width of the sections so as to extend beyond the upper and lower edges of said sections. Shafts 8 have their ends passing through the slots in the flanges and these ends carry rollers 9 which are adapted to engage the guideways 3. By the arrangement of slots and shafts the sections will be spaced apart when the door is raised but said sections will engage each other, under the action of gravity, when

the door is lowered. In order to make a tight joint between the sections I provide a groove 10 in the upper edge of each section to receive the lower edge of the adjacent section. Said groove may be formed by placing strips 11 on the sections, the upper edges of the strips being offset to provide the grooves. The shafts and slots will permit the door sections to be spaced apart far enough to permit the door to pass along the curved part of the guideways, as shown in Figure 3.

The means for raising the doors consist of a shaft 12 rotatably mounted in the roof of the car and having secured thereto the chains 13, the lower ends of which are adapted to be connected with the top of the doors by the hooks 13'. This shaft is provided with a sprocket 14 and a shaft 15 is located at the bottom of the car and is provided with a sprocket 16 and these sprockets 14 and 16 are connected together by the endless chain 17 so that when the shaft 15 is rotated the shaft 12 will also be rotated so as to wrap the chains thereon and thus raise the door. Shaft 15 is provided with a square end which projects beyond the car and is adapted to receive a crank handle or the like whereby the shaft can be manually rotated. The shaft is also provided with ratchet mechanism 18 for preventing retrograde rotation.

In order to hold the doors in raised or open position I form holes 19 in the guideways to receive bolts 20 for engaging the lower end of the door and thus holding it against downward movement.

From the above it will be apparent that when a door is to be opened it is simply necessary to place the crank on shaft 15 and turn the same so as to rotate shaft 12 by means of the chain 17. The rotation of the shaft 12 will wind the chains thereon and thus the door will be lifted. During this lifting action the sections of the door will be separated so that they can follow the curved part of the guideways. After the car is empty it is simply necessary to swing the dog of the ratchet mechanism 18 out of engagement with its ratchet so as to permit the door to drop by gravity. When the lower section of the door strikes the sill the other sections will continue to move downwardly until they rest in the grooves 10.

It is thought from the foregoing description that the advantages and novel features of my invention will be readily apparent.

I desire it to be understood that I may make changes in the construction and in the combination and arrangement of the several parts, provided that such changes fall within 5 the scope of the appended claims.

What I claim is:—

1. In combination with a car having guideways at the sides of its door opening, a door formed of a number of sections, each 10 section having flanges at its ends, said flanges having slots therein, the slotted portions of the flanges extending beyond the upper and lower edges of each section and each section having a groove at its upper edge for receiving the adjacent section, shafts passing through the slots, rollers on the ends of the shafts for engaging the guideways and means for raising the door.
2. A car door formed of a plurality of 20 sections, slotted flanges provided on each section at the ends thereof and being of a greater length than the width of the sections, said car having door openings therein and guideways formed at the sides of each door 25 opening, said guideways being extended beneath the roof of the car and the extended portions being of curved formation to conform to the shape of the roof, shafts passing through said slots and rollers on the ends of

the shafts which are adapted to engage said 30 guideways and means for raising the doors of the car.

3. A car having guideways at the sides of the door openings, said guideways having upward extensions curved along the roof of 35 the car, a door formed of sections which are movably connected together and rollers provided thereon to engage the guideways, slotted flanges provided on each section, means for raising said door consisting of a 40 shaft rotatably mounted in the roof of the car and chains secured thereto, hooks adapted to connect the lower ends of the chains with the top of the doors, a sprocket provided on said shaft and a second shaft located at the bottom of the car which is provided with a sprocket, an endless chain adapted to connect said sprockets together, one of said shafts having a squared end and a crank handle provided thereon for manually rotating said shaft, latch means provided on said shaft for preventing retrograde movement and means for holding the doors in raised or opened position.

In testimony whereof I affix my signature.
FRANK HIDOCK.
